(57) **CLAIM**

The ornamental design for a holder for repositionable notes, as shown and described.

DESCRIPTION

FIG. 1 is a top view of a holder for repositionable notes in accordance with the new design;

FIG. 2 is a rear view thereof;

FIG. 3 is a front view thereof;

FIG. 4 is a bottom view thereof;

FIG. 5 is a right side view thereof, the left side being a mirror image thereof;

FIG. 6 is a top isometric view thereof; and,

FIG. 7 is a bottom isometric view thereof.

The broken lines shown in FIGS. 2 to 7, which define the bounds of the claimed design, form no part thereof.
